COMBINATION POCKETKNIFE AND CIGARETTE LIGHTER

Jack Polineovsky, New York, N. Y.

Application July 20, 1953, Serial No. 26,044

Term of patent 14 years

(Cl. D48—27)

To all whom it may concern:

Be it known that I, Jack Polineovsky, a citizen of the United States of America, residing in the Borough of Manhattan, city of New York, county of New York and State of New York, have invented a new, original, and ornamental Design for a Combination Pocketknife and Cigarette Lighter, of which the following is a specification, reference being had to the accompanying drawing, forming part thereof.

I claim:

The ornamental design for a combination pocketknife and cigarette lighter, as shown.
